UNITED STATES PATENT OFFICE.

PHILIP N. BRAUN, OF SYRACUSE, NEW YORK, ASSIGNOR TO THE PROSPERITY COMPANY INC., OF SYRACUSE, NEW YORK, A CORPORATION OF NEW YORK.

SHIRT-PRESSING MACHINE (CUFF, YOKE, AND NECKBAND).

Application filed April 14, 1926. Serial No. 102,003.

This invention relates to pressing machines particularly shirt pressing machines, and has for its object a particularly simple and efficient construction by which a plurality of pressing operations are performed at the same time on one machine.

The invention consists in the novel features and in the combinations and constructions hereinafter set forth and claimed.

10 In describing this invention reference is had to the accompanying drawings in which like characters represent corresponding parts in all the views.

Figure 1 is a front elevation of one form 15 of pressing machine embodying my invention.

Figure 2 is a plan view of the ironing faces of the lower units the position assumed by the neck band and yoke being indicated 20 in dotted lines.

Figure 3 is a fragmentary elevation looking to the left, Figure 1 of the upper and lower pressing elements.

As will be understood by those skilled in 25 the art, in commercial laundries, shirts are pressed by a plurality of operations performed on different machines or in some instances on the same machine by different operations, that is the neck band is pressed in 30 one operation or on one machine, the front of the shirt pressed in another operation, the back in another operation, the cuffs in another operation.

By my invention a plurality of these operations which have heretofore been performed on different machines or at least at different times are performed in one operation.

This pressing machine, therefore, comprises 40 cooperating upper and lower pressing elements having relative movement, one toward and from the other, each pressing element comprising a plurality of units shaped to perform different operations or act upon different portions of the shirt requiring different pressing operations. The machine also comprises cooperating pressing elements shaped to press the neck yoke and contiguous portions of the shirt.

50 In the illustrated embodiment of my machine, the pressing elements are shaped to press the neck band and yoke, and the cuffs of a shirt in one operation and each pressing element, therefore, comprises a central unit shaped to iron the yoke and the neck

band and side units on opposite lateral sides of the central unit for ironing or pressing the cuffs of the shirt.

1 and 2 designate the upper and lower elements, as a whole, the upper element being 60 movable toward and from the lower and supported by a frame lever 3 of any well known construction, suitably mounted or pivoted to the frame 4 of the machine to move toward and from the lower pressing 65 element. The lower pressing element 2 is suitably mounted on the frame 4. The upper pressing element is actuated in any suitable manner either by hand, foot or by power, and as the various forms of manual, 70 pedal or power means are well known to those skilled in the art, description of any actuating means is thought to be unnecessary. Each pressing element consists of three units and the units of the upper and 75 lower elements are complementary to each other.

5 designates a central unit of the lower pressing element, 6 is the complementary central unit of the upper pressing element 1. 80

7 are the outer or side units of the lower element 2, and 8 the complementary units of the upper pressing element 1. The central unit 5 is shaped to press the neck band and yoke of a shirt and is in the form of a buck 85 having downwardly and laterally inclined pressing faces 10 on which the neck band of a shirt is pressed and a forward somewhat circular extension 11 at the apex of the buck or at the highest portions of the faces 10 for 90 pressing the yoke. As here shown this buck 5 is also formed with a flat surface 12 at the apex of the buck and the extension 11 is in the plane of the surface 12. Owing to the somewhat circular shape of the extension 11, 95 its side edges converge inwardly toward the middle of the extension as they approach the front edge of the surface 12 of the buck 5 and thus form clearances into which the portions of the shirt adjacent the neck band can 100 enter. The lower pressing element 5 thus has downwardly and laterally extending pressing faces with the shelf 11 extending forwardly from the highest portion of the body or major part of said element and in 105 front of the front edges of the body. This extension 11 is shown as supported by brackets 13 formed on the buck 5. Only a small portion of the central unit is used to iron a neck band, but the central unit is made wide 110

enough from front to rear to accommodate the widest collars of shirts and blouses, etc., having attached collars instead of neck bands to which detachable collars are attached.

The central unit 6 of the head 1 is provided with wings 14 having surfaces complementary to the surfaces 10 of the buck 5, and a forward extension 15 complementary to the extension 11.

The bucks 7 and heads 8 are of any well known construction for pressing cuffs and are here shown as having diverging pressing surfaces, the pressing surfaces of the head 8 being in the form of an inverted V, and those of the buck 7 complementary thereto.

In usual practice, other operations such as ironing the shirt front and back having been performed on other machines, (and usually these operations are so performed), the pressing of the cuffs finishes the operation, and the only pressing that the neck yoke gets is that performed while the back and the front are being pressed, also heretofore when cuffs were being pressed no other pressing operation was being performed at the same time. Or oftentimes the cuffs and neck band are ironed first and second by different operations. Heretofore the front of the yoke, or that part of the shirt within the neck band, when the shirt is folded has been ironed on a separate machine or by hand. As is well known, the purpose of ironing the front face of the yoke is mostly to make the package or folded shirt look neat and finished.

By this machine the yoke and neck band are pressed at the same time as the cuffs and the entire operation requires no more, or very little more than the pressing of the cuffs, and very much more satisfactory results in shirt pressing are brought about more quickly than by other methods of pressing or machines.

What I claim is:—

1. A shirt pressing machine comprising upper and lower pressing elements, one of which is movable toward and from the other and means for actuating the movable element, the lower element having downwardly and laterally inclined pressing faces and a central, substantially flat pressing face at the apex of the inclined faces, and also having a forward extension in the plane of the apex portion of the pressing element and extending forward beyond the edge of the inclined faces.

2. A shirt pressing machine comprising upper and lower pressing elements, one of which is movable toward and from the other and means for actuating the movable element, the lower element having downwardly and laterally inclined pressing faces and a central, substantially flat pressing face at the apex of the inclined faces, and also having a forward extension in the plane of the flat

face, the side edges of the forwardly extending portion converging inwardly toward the median line of the extension to form clearances as they approach the forward edge of said inclined faces.

3. A pressing machine comprising upward and lower pressing elements, one of which is movable toward and from the other and means for actuating the movable element, said element having complementary pressing faces and the lower element being provided with downwardly and laterally inclined pressing faces and a forward extension in line with the upper apex portion of the inclined faces and the forward extension extending beyond the edges of the inclined faces.

4. A pressing machine comprising upper and lower pressing elements, one of which is movable toward and from the other and means for actuating the movable element, said elements having complementary pressing faces and the lower element being provided with a downwardly and laterally inclined pressing face and a forward extension in line with the upper apex portions of the inclined faces, the lateral edges of the forward extension converging inwardly toward the middle of the extension as they approach the front edges of the inclined faces to form clearances at the junction of the inclined faces and the forward extension.

5. A shirt pressing machine comprising upper and lower pressing elements one having relative movement toward and from the other, means for actuating the movable element, the lower pressing element having a central flat pressing face and pressing faces inclining downwardly and laterally from the central flat face with their front edges inclined rearwardly and the lower pressing element having a forwardly extending shelf in line with the central flat face, the lower pressing element being designed to receive a neck back along the margin of its flat and inclined faces with the neck yoke on said shelf.

6. A pressing machine comprising upper and lower coacting pressing elements, one of which is movable toward and from the other, and means for actuating the movable element, the lower element comprising a body having downwardly and laterally extending faces and a forward extension at the highest portion of the body on the front side thereof, the forward extension extending forwardly beyond the front edges of the downwardly inclined faces of the body.

7. A pressing machine comprising upper and lower coacting pressing elements, one of which is movable toward and from the other, and means for actuating the movable element, the lower element comprising a body having downwardly and laterally extending faces and a forward extension at the

highest portion of the body on the front side thereof, the forward extension extending forwardly beyond the front edges of the downwardly inclined faces of the body, the 5 side edges of the forwardly extending portion converging inwardly toward the medial line of the extension to form clearances as they approach the forward edges of the front edge of the body.

In testimony whereof, I have hereunto 10 signed my name, at Syracuse, in the county of Onondaga, and in the State of New York, this 2nd day of April, 1926.

PHILIP N. BRAUN.
